UNITED STATES PATENT OFFICE.

OWEN J. SUND, OF TACOMA, WASHINGTON.

DUPLEX SHOE POLISHER.

Application filed August 11, 1926. Serial No. 128,571.

My invention relates to polishers for shoes and other articles, and has for its objects, first, to improve the construction of the polisher whereby the layers of felt may be securely held together; second, to provide a duplex casing therefor, either half of which may be removed to expose one, or the other, polishing surface of the felt, for use with either black or tan, or other colored shoes, 10 the remaining half of the casing acting as a handle for the polisher; and third, to provide a securing device whereby the respective portions of the casing may be removably held on the polisher. Further objects are to 15 provide a container for the polisher whereby it may be packed in a traveling bag with clean clothing without danger of soiling the articles with which it comes in contact; and to provide a cheap, strong, effective and simple duplex polisher which may be used to 20 polish, with its two surfaces, shoes of two different colors, and which will not cause the color of one surface to be transferred to the other surface through the use of a common 25 cover for the two surfaces.

I attain these and other objects by the devices and arrangements illustrated in the accompanying drawings, in which:—

Fig. 1 is a perspective view of my improved duplex shoe polisher when closed; Fig. 2 is a similar view showing it ready for use, one cover having been removed to expose one polishing surface and the other cover being retained in place to serve as a handle therefor; Fig. 3 is a similar view showing the polisher entirely removed from its enclosing covers; Fig. 4 is a cross-section of my improved duplex shoe polisher, when closed; and Fig. 5 is a perspective view of one of 40 the two latching devices, adapted to removably hold both covers on the polisher.

Similar numerals of reference refer to similar parts throughout the several views.

The polisher comprises a plurality of layers 1 of heavy felt cloth, each substantially square in shape and all of the same size. These layers 1 of cloth are firmly bound together by means of a metal strip or belt 2, which passes around the center of the polisher, and also by a wire 3 which passes twice through each of the said layers and also through the end portions of the said belt 2. Thus two edges of all the layers 1 may be exposed for use as polishers, and therefore the same device may be used on two different colored shoes (Fig. 3).

The belt 2 is provided with a central bead 4 extending entirely around the polisher.

The casing or container for the polisher comprises two similar covers 5 and 6, each 60 adapted to enclose one half of the polisher. The sides of the said covers 5 and 6 slip over the belt 2 and extend substantially to the bead 4 therein.

The covers are each separately locked or latched to the belt 2, on both sides of the polisher, by means of two similar latch pieces, one of which is shown in Fig. 5. The latch piece is secured to the inner side of the belt 2, at the center of the side portions thereof, between it and the felt of the polisher, by means of a central rivet 7. The latch piece comprises a central longitudinal strip 8, preferably of spring metal, having two operating lugs 9 extending horizontally outward therefrom at its ends; and two latch arms 10 extending vertically, up at one end and down at the other, each with latch lugs 11 extending outward therefrom. The operating lugs 9 are substantially on the central axis of the latch piece and extend outward through suitable openings in the bead 4 in the belt 2 and are each adapted to be pressed inward to bend the half of the strip 8 and thus push inward the adjacent arm 10 with its latch lug 11. The latch lugs 11 are positioned on the two sides of the central axis of the strip 8 and each passes through suitable holes in the belt 2 and in the sides of the covers 5 or 6, as the case may be, and are 90 adapted to engage the edge of the hole in the cover to prevent its removal from the belt 2 until the corresponding operating lug 9 is pushed inward, as above, when the latch 11 also moves inward and releases the said 95 cover.

Thus it will be seen that when both covers 5 and 6 are in place (Fig. 1), the polisher is completely enclosed and the device may be packed with perfect assurance that none of the stain on either polishing surface of the felt pads 1 will soil the goods with which it is packed. Also, it is evident that, if the cover 5 closes the side of the polisher which is used for black shoes and the cover 6 similarly closes the side used for tan shoes, when the cover 5 is removed, by pressing in the two lugs 9 controlling the two latch lugs 11 engaging the said cover, the polisher is ready to be used on black shoes and that the cover 6 then becomes the handle or grip of the polisher; and similarly, when the cover

6 alone is removed, the polisher is ready to be used on tan shoes and the cover 5 then becomes the handle or grip thereof (Fig. 2).

Also, in practice one cover 5 or 6 alone is removed at a time, therefore it is evident that the stain of the felt pads 1 on one side will not be transferred to the felt pads on the other side through the accidental interchange of the covers, because one cover is 10 always retained in place for use as a handle.

Having, therefore, described my invention, what I claim is:—

1. A duplex shoe polisher comprising a polishing body; a central metal belt surrounding said polishing body and dividing

it into two distinct parts each of which is adapted to act as a polishing surface; and two removable covers, each enclosing one such polishing surface and passing over the said belt.

2. A duplex shoe polisher as set forth in claim 1, together with latch means mounted on the belt and engaging both of said covers whereby either of said covers may be removed from the belt to expose one such 20 polishing surface for use; and whereby the remaining cover is adapted for use as a grip for the polisher.
